METHOD AND APPARATUS FOR CONTACTING GASEOUS FLUIDS WITH SOLIDS Pieter J. Schoenmakers, Delft, Netherlands, assignor to
Shell Oil Company, a corporation of Delaware

Application January 27, 1956, Serial No. 561,881

Claims priority, application Netherlands January 31, 1955

17 Claims. (Cl. 208—176)

This invention relates to a new method and apparatus for the contacting of gaseous fluids with fluidizable solids. One aspect of the invention relates to a process and apparatus for continuously effecting a rapid change in temperature in a gaseous fluid, or the rapid vaporization of a vaporizable liquid, by contact with a fluidizable solid of different temperature.

The process of the invention is particularly applicable in the treatment of gaseous fluids (by which I mean to include true gases, vapors, and also liquids which are immediately vaporized upon contact under the conditions) at high temperatures where undesired reactions tend to occur. The process is also advantageous in carrying out many vapor phase reactions at high temperature where it is desirable for the reaction to proceed very rapidly in order to avoid undesirable side reactions. By rapid reactions or treatments are understood reactions or treatments which proceed and take place in less than 0.5 second. On the other hand, the process and apparatus of the invention are advantageous for the rapid cooling of a vaporous high temperature reaction product whereby side reactions are repressed and/or the reaction product is frozen at or near a high temperature equilibrium state. By applying both of these simultaneously it is possible to obtain both a very rapid heating and a very rapid cooling after a very short or relatively long residence time at the high temperature or in other words a substantially square temperature versus time curve.

In many cases it is desirable or necessary to contact one or more gaseous fluids with a solid material and in many of these cases the efficiency and duration of such contact are quite important.

In the past it has been the usual practice to pass the gaseous fluid through a bed of pieces of the solid which were either in a fixed position or slowly moved through the contacting zone. In these cases the solid is in the form of relatively large particles upwards of $\frac{1}{16}$ inch in diameter since otherwise the pressure drop through the bed of particles becomes inordinately large.

Also, the so-called fluidized solid technique has come into wide-spread use for these purposes. This technique is not applicable for all solids but is applicable and often advantageous when the solid is one which can be fluidized, i.e. be brought into a fluidized (pseudo liquid) state by suitable aeration with a gaseous fluid. The first requirement of the solid in this respect is that it be in powdered form, i.e. have a range of particle sizes from a minimum of a fraction of a micron up to a maximum of about 2 millimeters mean diameter. Although it is not necessary that this full range of particle sizes be present it is generally necessary that the particles have a substantial range of sizes, i.e. a factor of 3 or more, within these limits. The second requirement of the solid is that the shape and/or electrical properties of the solid particles be such as to allow fluidization. Flake material, needle shaped particles, flocculant precipitates, some powders consisting entirely of very small particles, e.g. less than

2

5—20 microns, most magnetic solids, and solids consisting of only large particles, e.g. greater than about 2 millimeters, are difficult or impossible to fluidize with a gaseous fluid. The suitability of powdered solids in this respect is best indicated by their angle of repose. Thus, the above named materials, and others which cannot be properly fluidized, have a high angle of repose, e.g. 80° or more for burnt gypsum and talcum powder. Solids which may be fluidized generally have an angle of repose of 55° or less and the better ones an angle of repose of about 45° or less.

When the above requirements are met the solid may be fluidized. In the fluidized state the powdered solid acts in many ways like a true liquid, e.g. it seeks its own level; it is capable of exerting a "hydrostatic" head; it can be pumped or poured much like a molten metal.

One of the characteristics of a fluidized powder is its cohesiveness. For example, in contacting a gaseous fluid with a fluidized solid it is common, e.g. in conventional fluidized catalyst catalytic cracking, to pass the gaseous fluid up through a bed of the fluidized powder at a superficial gas velocity which is considerably above the free fall velocity of the particles of the powder as calculated by Stokes' law, and yet, as is well known, only a very small amount of the powder is torn away from the fluidized bed and carried by the issuing gaseous fluid. For various reasons the individual particles tend to approach or become closely associated with others, as a result of which the particles do not behave as individual particles and the mass behaves much like a liquid.

On the other hand, since this cohesive tendency increases with decreasing particle size (which accounts for the difficulty in fluidizing powders in which all of the particles are of extremely small and uniform size, e.g., less than 5 microns, and also large particles) the solid may contain, or even consists mainly of, quite small particles, e.g. average V/S diameter less than 500 microns.

In the past this fluidized state has been obtained by passing a gas, or vapor, or in some cases a liquid which is rapidly vaporized upon contact with the solid, up through a bed of the powdered solid.

If a gas is introduced into the bottom of a settled bed of fluidizable solid at very low rate, the gas simply passes through the minute interstices and out of the top of the bed without affecting the bed itself. If the gas velocity is increased slowly a point is reached at which the bed expands somewhat and the particles move about. The point at which this occurs may be called the minimum fluidization gas velocity. This minimum fluidization gas velocity depends somewhat upon the particular solid in question but is usually of the order of 0.01—0.20 foot per second for most fluidizable powders. At this minimum fluidization gas velocity the bed has usually expanded by approximately 12% of its original, i.e. settled, volume. If the gas velocity is further increased the bed of powder expands somewhat further with no appreciable increase in pressure drop through the bed until a maximum limiting velocity is reached above which the powder is blown upward with the gas. Beyond this point a fluidized state no longer exists and the powder is simply dispersed as a suspension of individual particles in the gas. In the region of gas velocities giving a fluidized state the gas passes through the somewhat expanded interstices, although in many cases, due to maldistribution of the gas, bubbles form and pass up through the pseudo liquid powder. Thus, in the case of fluidized solids, the expansion of the interstices, within the limitations allowing the fluidized state, is produced by the energy of the gas forced up through the bed of powder.

The phenomenon of fluidization of powders has long been known and the cohesive behavior has been qual-

tatively recognized. The magnitude of this cohesion, however, has, to the best of my knowledge, not been measured nor appreciated.

The present invention is based on the discovery that it is in many cases advantageous with astounding results to pass the gaseous fluid to be contacted horizontally (or approximately so) through a free falling body of the fluidized solid.

It has hitherto been proposed to pass various gaseous fluids through a free falling shower of solid material, but in these prior instances the conditions were such that the particles of the solid behaved as individual or discrete particles. For example, if a fine powder is passed through a sieve into a free falling space the particles behave as a shower of discrete particles rather widely spaced as, for example, in a rain. Passage of a gaseous fluid horizontally through such a shower affords only a very mediocre contact efficiency and if the velocity of the gaseous fluid is appreciable, the individual particles are carried with the gaseous fluid.

If large particles are allowed to drop through an orifice into a free falling space, the particles again behave as individual particles and also give only an open shower, again much like rain, which likewise affords only a mediocre contact with a gaseous fluid passed horizontally therethrough. In the case of large particles this is due mainly to two factors. The first is that if large particles such as granules, spheres, pellets, etc. which are not fluidized are allowed to flow through an orifice into a free fall space, the mass flow of solid through the orifice does not obey the laws which apply to fluids and is considerably smaller. Even with orifices with diameters many times the diameter of the particles, the resulting shower of particles is loose, non-coherent, and totally different from the close coherent nature of a fluidized solid. The second factor is the natural tendency of individual free falling granules to separate. It is a well known fact of elementary physics of free falling bodies that if two particles are released into a free falling space, one immediately after the other, the distance between them continues to increase up until the time where they attain their maximum or terminal free fall velocity. This is due to the fact that the distance of fall is a function of the square of the time of fall. If one passes a stream of pellets, for example, through an orifice into a free falling space the pellets separate. However, for the case of fluidized powders, within wide limits, this separation does not take place to any appreciable extent even over a considerable and practical distance of free falling height. This is due to the cohesive nature mentioned and to the relative low limiting free fall velocities of particles of the small size range in question.

There is a distinct difference in the behavior of a free falling mass of fluidized solids and free falling discrete particles of either large or small size when a gaseous fluid is passed horizontally therethrough. If one has an annular orifice and passes through this orifice into a free falling space powdered solid at such a mass rate that the particles act more or less as an annular shower of discrete particles, and if a gas is passed horizontally outward through the free falling annular shower at a velocity less than the terminal free fall velocity of the particles of the powder, the particles tend to move with the gas so that the shower of particles increases considerably in diameter a short distance below the orifice giving a cone shaped shower.

In the case of a free falling mass of fluidized powder, on the other hand, the cohesion mentioned is quite apparent. The annular sheet does not become conical but remains substantially cylindrical even when the horizontal velocity of the gas passing therethrough approaches the terminal free fall velocity of the individual particles. If the velocity of the gas passing through the sheet is further increased the sheet retains this substantial cylindrical shape until at quite high velocities of the gas the

sheet bulges and then suddenly ruptures into a number of incoherent masses. In other words, it acts like a liquid.

In the case of a shower of large particles, e.g. above 1 mm. diameter, the spreading into a cone does not occur at nominal gas velocities due firstly to the fact that the terminal free fall velocity of the such larger particles is much higher than the horizontal gas velocity and hence little angular horizontal displacement results, and secondly to the fact that due to the above-described separation phenomenon the shower offers practically no resistance to even considerable horizontal flows of gas; in other words, there is only a mediocre contact between the free falling relatively widely separated granules of solids and the gas. If the gas velocity is substantially increased, however, even these comparatively large particles behave just as described for discrete particles of powder. Thus, a conical configuration results and the angle of the cone increases with increasing gas velocity without any rupture as described above.

In the manner of contacting according to the invention, the effluent gaseous fluid passing through the mass of free falling solid entrains an unexpectedly small amount of this solid at gas velocities below that at which the sheet mass is ruptured.

I have found that by passing a gaseous fluid through such a coherent free falling stream of fluidized powder an unexpectedly excellent contact can be obtained with an extremely short contact time. Thus, for instance, I have passed vapors through such a free falling stream of fluidized solid of only about 7 millimeters' thickness and have thereby increased the temperature of the vapors from a low temperature to within 5° C. of the temperature of the solid in the 900° C. temperature range. This far surpasses any other method known to me for effecting extremely rapid heating of a gaseous fluid in a continuous manner.

According to the invention the gaseous fluid to be contacted is passed horizontally through a free falling mass of the fluidized solid. As will be described in more detail below, certain conditions are essential and others are highly desirable in order to obtain this sort of contact.

Firstly, the solid must be one which meets the above-described requirements and is therefore fluidizable. One suitable material which has been extensively used in various studies leading to the invention and in pilot plant operation in the production of olefins from paraffin wax, is a fine silica sand having the following properties:

Volume/surface mean particle diameter=180 microns;
True specific gravity=2.660 g./cc.;
Specific gravity in the fluidized state at minimum fluidization gas velocity=1400 kg./m.³.

55	Size Distribution						
	Sieve Aperture in Microns.....	420	210	177	150	125	105
Percent Weight Undersize.....	97.6	64.0	30.2	14.6	5.0	3.1	

Secondly, the free falling mass of fluidized solid must be obtained by gravity flow through an orifice from a well fluidized bed of the solid. When the source of supply is a well fluidized bed it has been determined that the mass flow rate, i.e. discharge rate through the orifice, conforms to the following formula:

$$M = C\rho\sqrt{2gh}$$

wherein:

M =mass velocity in kg./m.² sec.

C =a proportionality factor

ρ =density of the fluidized solid in kg./m.³.

g =gravity acceleration in m./sec.².

h =depth of fluidized bed above the orifice in meters

Thus, the mass flow is proportional to the 0.5 power of the pressure drop and very large mass flows may be ob-

tained at reasonable pressure drops. For the above-mentioned sand the factor C has been determined to be very close to 0.50. The discharge rate for non-fluidized material through an orifice is, on the other hand, proportional to only about the 0.2 power of the pressure drop and as a result of this the mass flows are much less.

This dependence of the mass velocity of the fluidized solid in accordance with the 0.5 power of the head allows the mass transfer to be varied or adjusted during the processing by adjusting the head within practical limits and this is an important advantage of the process. The head may be adjusted by adjusting and maintaining the desired depth of fluidized bed above the orifice and/or, within limits, the pressure above said bed. The methods for adjusting and maintaining the depth of a fluidized bed in a vessel and/or the pressure above said bed are well known and do not require detailed description.

The discharge orifice may be of any length and of any width above a minimum of about 5 millimeters. It may be rectangular in shape but is preferably an annular orifice. The width of the orifice is preferably substantially uniform over its length and should contain no obstructions which cause the free falling mass issuing therethrough to vary in thickness, since otherwise an uneven falling mass is obtained which is easily ruptured by even relative low mass velocities of the gaseous fluid passing therethrough.

It has been found that in order to obtain a very uniform, dense, free falling mass of the fluidized solid, the arrangement of the orifice in vertical section is of some importance. The preferred arrangements are illustrated diagrammatically in Figures 17, 18, and 19 of the accompanying drawings. These figures, as well as Figures 20-22, are very diagrammatic illustrations of the orifice arrangement in cylindrical vessels and are believed to be self-explanatory. Other shapes such as those illustrated in Figures 20, 21 and 22 have been used and are operative when the width of the orifice is large compared to the size of the particles, e.g. greater than 100:1, but are less preferred. The shapes illustrated in Figures 20, 21 and 22, in particular, tend to give cavities or thin spots in the free falling mass which lower the resistance to rupture by the gaseous fluid and therefore allow only low mass velocities of gaseous fluid to be contacted. This is believed to be due to the squeezing action of the decreasing horizontal cross section above the orifice proper which decreases the fluidization and therefore curtails the mass flow. Thus, the fluidized mass is preferably discharged from the fluidized bed through an aperture with no, or at least a minimum passage through any confined channel and especially a channel of constricting hydraulic radius. The orifice consists preferably of an aperture in a plate, e.g. as in Figures 17 and 18 as compared to Figures 20-22. Thus, an annular ring or other orifice of substantial height connecting the fluidized bed with the free falling space, e.g. Figure 20, gives less satisfactory results. However, in the arrangement such as illustrated in Figure 19 where an annular orifice is used, one boundary of the orifice, preferably the inner side, may be extended somewhat into the free falling space.

It is, on the other hand, advantages to provide part of the free falling sheet mass of solid with a suitable shield which is spaced at some small distance from the sheet itself as illustrated in Figures 18 to 22.

In order to prevent passage of the gaseous fluid around the sheet rather than through it, the orifice must extend across the entire section of the confining chamber so that the sheet extends from wall to wall, or the orifice must in cross section constitute a closed figure, e.g. an annulus, so that the sheet has a cylindrical or other closed shape.

Also, in order to prevent the gaseous fluid from passing under the sheet, the sheet must terminate at its lower end in a second bed of the solid which must be maintained fluidized. While it is essential that this lower bed of the solid be maintained fluidized by the use of a suit-

able aeration medium, it is found desirable to maintain the flow rate of said aeration medium at a rather low value approaching the minimum fluidization velocity. The maintaining of the lower bed of the solid in a fluidized condition tends to stabilize the sheet against rupture by the gaseous fluid passing therethrough. The aeration medium passing up through the lower fluidized bed strips gaseous fluid from the solid and passes up on both sides of the sheet. Thus, in the case of a cylindrical sheet of the solid with gaseous fluid to be contacted being introduced within the cylinder, some of the aeration medium passes up within the cylinder and through the sheet. This aeration medium is removed from the apparatus with the contacted gaseous fluid. Any suitable aeration medium may be employed; it is, however, generally a different gaseous fluid than the gaseous fluid to be contacted and is usually an inert material, e.g. steam, which may be easily separated from the contacted gaseous fluid in a subsequent separation step, e.g. partial condensation.

The sheet is confined in an essentially vapor tight vessel. The gaseous fluid to be contacted is introduced into the vessel at one side of the sheet and removed from the other side of the vessel opposite, or in the case of a sheet which is a closed figure the gaseous fluid is introduced either within the sheet or or outside of it and the contacted gaseous fluid is withdrawn from outside or inside, respectively, of the sheet. The gaseous fluid, is in any case, forced to pass through the sheet.

Various arrangements are illustrated diagrammatically in Figures 1 through 12 of the accompanying drawings.

Figures 1 and 2 diagrammatically illustrate the longitudinal and cross section, respectively, of an arrangement which operates with a flat sheet.

Figures 3 and 4 illustrate diagrammatically the longitudinal and cross section, respectively, of an arrangement operating with a cylindrical sheet.

Figures 5 and 6 illustrate diagrammatically the longitudinal and cross section, respectively, of an arrangement in which there are two flat sheets, one being cold and the other being hot.

Figures 7 and 8 illustrate diagrammatically the longitudinal and cross section, respectively, of an arrangement in which there are two cylindrical sheets, one being cold and the other hot.

Figures 9 and 10 illustrate diagrammatically the longitudinal and cross section, respectively, of an arrangement in which there are two hot flat sheets.

Figures 11 and 12 illustrate diagrammatically the longitudinal and cross section, respectively, of an arrangement in which there are two hot cylindrical sheets.

Figure 13 shows semi-diagrammatically the longitudinal section of an arrangement operating on the principle illustrated in Figure 3.

Figure 14 shows diagrammatically a modified construction of Figure 13 in which a louvered shield is provided.

Figure 15 illustrates diagrammatically an arrangement comprising two apparatuses connected to allow continuous cyclic operation.

Figure 16 illustrates semi-diagrammatically another modification of the arrangement shown in Figure 13 in which there are also included facilities for cycling the solid.

In the various figures like parts are indicated by the same reference numbers.

The arrangements illustrated in Figures 1 to 12 are for the sake of simplicity illustrated without baffles and also with the gaseous fluid being introduced only at one level.

These arrangements are operative without shields as illustrated but in practice the sheets are preferably shielded over a substantial part of their height by a depending baffle somewhat removed from the sheet on the side of the sheet through which the contacted gaseous fluid emerges, e.g. as illustrated in Figures 13 to 16. As described elsewhere the shield should on no account contact the sheet and is preferably removed from the sheet

by about 2 to 10 sheet thicknesses. Such shielding forces contacted gaseous fluid to flow downward parallel to the sheet.

When the gaseous fluid to be contacted is initially in the form of a forceable liquid which quickly vaporizes on contacting the sheet, it is best injected at a relatively high point near the top of the sheet as illustrated. However, when the gaseous fluid is initially in vapor form it may be introduced at a plurality of points of different elevation as well as in the horizontal arrangement illustrated. If the gaseous fluid to be contacted is introduced at a plurality of points, its jet head is less and there is considerably less tendency to rupture the sheet.

The sheet 1 in the apparatus according to Figures 1 and 2 is formed by flow of fluidized solid through slit 2 provided at the top of the vessel 3 which houses the sheet. The fluidized solid is introduced via a pipe 4 to the fluidized bed in the upper vessel 5 which bed is maintained in the pseudo-liquid state by aeration gas supplied via the line 9. The solid material comprising the free falling sheet is collected in the collecting device 6 in which a fluidized bed of the solid is maintained. Aeration gas to maintain this lower fluidized bed in a pseudo-liquid state is introduced by line 8. In the arrangement illustrated this collecting device is integral with the lower part of the vessel 3. The fluidized solid particles are withdrawn from the collecting device 6 by pipe 7. By altering the level of the fluidized bed in the upper section the mass of fluidized material passing through the slit orifice 2 can be regulated. The gaseous fluid which is to be contacted with the solid is supplied by one or more lines 10, 11, and 12 to one side of the sheet 1. In place of the separate lines a single distributing means extending over the whole width of the sheet may be used. The gaseous fluid, after passing through the sheet, is withdrawn on the other side thereof through line 13.

If the sheet consists of material which has a temperature considerably lower than that of the gaseous fluid to be contacted the gaseous fluid is cooled very rapidly on passing through the sheet.

If, on the other hand, the temperature of the sheet is considerably higher than the temperature of the gaseous fluid supplied through lines 10, 11, and 12, the gaseous fluid is heated very rapidly on passing through the sheet. The heated gases being withdrawn by line 13 may be quenched by means of a quenching medium introduced via line 14.

The described arrangement is quite suitable for many reactions which may be carried out either thermally or catalytically. For instance, the thermal cracking of paraffin waxes to produce olefins, and the thermal coking of tars or pitches are examples of treatments for which this system is suited. The system may also be used to carry out reactions between two or more gases which have to be raised rapidly to the desired reaction temperature. Thus, for example, separate reactants may be supplied separately via the lines 10, 11, and 12. The mixture is rapidly heated to the reaction temperature upon being passed through the sheet 1 and the vapors afterwards react in the space downstream with respect to the sheet 1. The reaction product is removed by line 13 as before. If two separate reactant gases are mixed first and then supplied by lines 10, 11, and 12, the reaction is at least initiated and in some cases may be substantially completed during the exceedingly short time that the mixture is passing through the sheet.

In the arrangement illustrated in Figures 3 and 4 the orifice is an annular slit 15. The fluidized solid particles in the supply means 5 flow through this annular slit to form a cylindrical sheet 16 in vessel 3.

Any closed figure may be chosen for the cross section of the sheet. This cross section is preferably a circle (annulus) (as illustrated in Figure 4) since in this case the gaseous fluid to be contacted may be more evenly distributed when introduced centrally via the nozzle 17. If

the gaseous fluid to be contacted is initially in the gaseous state it will be introduced simply through an open ended pipe or through a conventional gas distributing nozzle. If the gaseous fluid to be contacted is initially a liquid which is easily and rapidly vaporized upon contact with the solid, the nozzle 17 is preferably one which will atomize the liquid such, for example, as a swirl chamber atomizer.

By using a wider orifice the sheet may be made up to any desired thickness. However, since the contact is so efficient it will rarely be necessary to have the sheet more than a few inches thick.

Greater throughput capacity may be obtained by increasing the height of the sheet and by increasing the diameter of the cylinder, preferably the latter. If the diameter of such a cylindrical sheet is greatly increased, e.g. to several feet, the space within the cylinder becomes rather large. In order to decrease the residence time of the gaseous fluid in this space an axially placed dummy of cylindrical or conical shape somewhat smaller than the space may be provided. The gaseous fluid is thereby caused to occupy only that part of the space between the dummy and the sheet.

In this arrangement also one or more gaseous fluids may be supplied either separately or in admixture and contacted by passage through the sheet. Also, as in the arrangement shown in Figures 1 and 2, an additional gaseous reactant may be supplied into the space (by means not shown) downstream with respect to the sheet in order to react this gas with the gases issuing from the sheet.

The quenching of the contacted gaseous fluid may be effected as described by injection of a suitable quenching liquid via line 14 into the product line 13. The quenching may, however, be effected even more promptly by passing the gaseous reactant product issuing from the sheet directly through a second sheet having a low temperature. A very rapid cooling of the gaseous fluid can thereby be effected immediately following the rapid heating. Thus, an arrangement similar to that illustrated in Figure 1 may be provided with a second sheet of relatively cold material as illustrated in Figures 5 and 6. Referring to these figures the second sheet 18 is at a relatively short distance from the hot sheet 1. Cooled solid is supplied into an upper fluidized bed 20 by means of line 19. As before, the solid is maintained in a well-fluidized state by the injection of a suitable aeration medium introduced by line 21. The orifice for this second sheet is the slit 22. This sheet is collected in the lower collecting device 23 which is filled with the solid maintained in a fluidized state by injection of a suitable aeration medium via line 24. The hot and cold fluidized materials are withdrawn from their respective collecting devices by lines 7 and 25, respectively.

In a similar manner the hot and cold sheets may take the form of two concentric cylinders as illustrated in Figures 7 and 8. The gaseous fluid to be contacted is supplied at a point or points in the interior of the inner sheet 16 through the nozzle 17. The gaseous fluid passes through this sheet whereby it is rapidly raised to a high temperature after which the hot gaseous product passes through the outer sheet 26 whereby it is rapidly cooled.

In the arrangement illustrated in Figures 9 and 10, there are two sheets, both of which are relatively hot. This arrangement is suitable for reacting gaseous fluids which have to be raised separately to the required reaction temperature. Thus, one of the fluids is supplied on the left of sheet 1 via the lines 10, 11, and 12 and the second gaseous fluid is supplied to the right of the sheet 1 via lines 26, 27 and 28. After these respective fluids pass through the sheets they react in the space within vessel 3 which is defined by the two sheets. The reaction product is removed through line 29 either with or without quenching.

In the arrangement illustrated in Figures 11 and 12,

there are likewise two hot sheets 16 and 16' in the form of concentric cylinders. One of the gaseous fluids is introduced on the outside of the outer cylinder and passes inward. The other gaseous fluid is introduced in the space within the inner cylinder and passes outward. The two pre-heated gaseous reactants react in the annular space between the two cylinders and are withdrawn by line 29.

Figure 13 shows an apparatus operating on the principle illustrated in Figure 3. The hot sheet 16 is supplied from the upper fluidized bed in chamber 5 through an annular slit. The sheet is therefore in the form of a cylinder. The solid material in vessel 5 is maintained in the fluidized state by supplying an aeration medium through line 9, the outlet of which is positioned below the level of the slit 15. This arrangement insures a regular supply of the fluidized solid according to the laws for liquid flow. The sheet falls into the collecting device 6 in which a bed of the solids is maintained fluidized by a suitable aeration medium introduced by line 8. The gaseous fluid to be contacted with the solid is introduced within the inside of the cylindrical sheet 16 by nozzle 17. The contacted product is discharged by line 13. In the arrangement illustrated the sheet 16 is shielded on the outside over practically its full length by wall 32 which is spaced some distance from the sheet.

In this particular arrangement a baffle 33 is provided which partly extends into the fluidized bed in the collecting device 6. The top of this baffle partly surrounds the wall 32 leaving some space.

In the arrangement illustrated in Figure 14 the wall 32' is provided with louvers arranged in such a way that the gas passing therethrough is sharply deflected in an upward direction. As before, the wall 32' is spaced away from the sheet so that the sheet falls free without wall friction.

In some cases a small amount of the finer particles of the solid are carried with the effluent gaseous fluid. Any material so carried in suspension may be separated with a cyclone separator 35 inserted in the discharge line 13. The gaseous fluid from which any substantial solids have been separated is withdrawn through the overflow 36 and the solid particles which have been separated flow by gravity down the dip leg of the cyclone to the seal pot 37 from which they pass to vessel 38. The fluidized solid in the collecting device 6 likewise overflows into the lower vessel 38. A line 39 leads from the vessel 38 to a heater (not shown) and a riser (not shown) for transferring the solid particles from the level of the discharge line 39 at least to the level of the inlet 4 of the upper vessel 5. The solid in the lower vessel 38 is further stripped of occluded material and maintained in a fluidized state by the injection of a suitable aeration medium. This material, as well as the aeration medium supplied by line 8 to the disengaging device 6, is removed with the product through line 13 and the cyclone overflow 36.

The gaseous fluid removed by line 36 after having been contacted with the solid usually contains some gaseous by-products of side reactions. While such side reactions are minimized by the use of the described method of contacting they usually cannot be totally avoided. After removing the desired product from the reaction mixture this residual gas may be advantageously utilized to fluidize the solid in the upper bed. For this purpose it may be introduced by line 9.

The apparatus illustrated in Figure 13 was used for the production of light olefins by short time, high temperature cracking of a heavy cyclic oil having the following properties:

Molecular weight..... 366
Normal paraffins..... percent 35
Isoparaffins+naphthenes..... do 63

The above-mentioned sand was used to form the screen which was 5 centimeters' internal diameter, 6.5 centime-

ter's external diameter, and 25 centimeters in length. The nominal throughput of the sand was about 12 tons per hour. The results are given in the following tabulation:

5	Temperature	° C	750	800	850
	Hydrocarbon throughput	kg./hour	40		
	Residence time (atomizer to quench)	seconds	0.4		
10	Conversion, weight percent on feed		80.2		
	Ethylene yield, weight percent on feed		24.4		
	Methane yield, weight percent on feed		8.2		

The same apparatus and sand were used for the short contact time high temperature cracking of a bright stock slack wax at temperatures between 750 and 850° C. and at a throughput rate of 40 kg./hour. The results are tabulated below:

Temperature, ° C	750	800	850	
20	Residence time (atomizer to quench), seconds	0.3	0.25	0.20
	Conversion, wt. percent on feed	63	76	84
	Ethylene yield, wt. percent on feed	13.5	16.5	26.7
	Methane yield, wt. percent on feed	4.2	5.2	9.8

25 The arrangement illustrated in Figure 15 consists essentially of two parts, A and B. These two parts are constructed in the same way as the apparatus shown in Figure 3. Part A serves to heat rapidly a fluid such as discussed in connection with Figure 3. Part B of the 30 apparatus serves to heat or regenerate the solid particles which are led from the collecting device 6 of the apparatus A via the riser 40 and the cyclone 41 to the supply hopper 42 of part B. Fluidization medium is supplied through the line 43 to the fluidized bed in vessel 42. The 35 discharge nozzle is again an annular slit 44 which produces a cylindrical sheet in vessel 45.

Fuel is supplied by line 47 and nozzle 48 together with combustion air by line 49 into the space enclosed by the 40 sheet. The combustion gases pass through the sheet thereby heating it and are withdrawn through line 50 connected to vessel 45. If the solid contains carbonaceous material this may be partly or completely burned off through the use of excess air in the combustion mixture.

The collecting device 51 of the apparatus B for the hot 45 material is provided with a supply line 52 for fluidization medium and at the same time forms the supply for the lower sheet 16 in apparatus A. The gaseous fluid to be contacted is introduced, as before, by nozzle 17 and the contacted product is removed by line 13. In this arrangement it will be noted that the sheet is housed for substantially its entire length without frictional contact by the depending baffle member 32. This baffle extends to within a short distance above the level of the fluidized bed of material in the collecting device 6. The material 50 of the sheet 16 is collected in the fluidized bed in the collecting device 6 from which it is withdrawn by line 7 to a riser 40 wherein it is carried to the cyclone 41 and from there back to the supply chamber 42 of the part B.

The apparatus shown in Figure 16 is similar to that 55 shown in Figure 13 but differs in the arrangement of the collecting device and baffle shielding around the sheet. The solid collected in the lower fluidized bed in vessel 38 passes by line 39 to the lift pot at the bottom of a vertical riser wherein it is elevated to a point above the level of the discharge passage 4. Air introduced at the bottom of 60 the lift pot serves as the conveying medium. The solid is separated from the air by an exceedingly simple but effective separator consisting of the large inverted hat placed directly above the exit of the vertical riser line. The side of the hat is of substantial depth as illustrated. 65 With this arrangement the solids are separated quite efficiently. The solids collected in the bed 41 are heated by combustion of a fuel therein.

Both exothermic and endothermic reactions may be 70 carried out by the process of my invention in order to

better control the temperature at which the reaction occurs, and/or to limit the time at such temperature.

As explained above, the processes and apparatuses of the invention are particularly suitable for the thermal cracking of paraffin waxes to produce olefins. This cracking is preferably carried out at temperatures of the order of 700-800° C. in the presence of steam, and in some cases oxygen. They also are suitable for the reaction of methane with steam to produce carbon monoxide and hydrogen. Oxidation reactions such as the reaction of methane with oxygen under conditions to produce acetylene or aromatic hydrocarbons can be also carried out in the manner indicated. Another application is in the oxidation of ammonia at temperatures of the order of 700-1000° C.

Also, various catalytic processes may be carried out such as the dehydrogenation of alkanes to alkenes using a chromium oxide catalyst or one of the various other known dehydrogenation catalysts.

In the chlorination of propylene to produce allyl chloride it is highly desirable to effect the reaction at a high temperature, e.g. above 500° C., with a very short contact time. The present method and apparatus are suitable for this type of reaction. The reaction between methane, ammonia, and oxygen to produce hydrogen cyanide and water using a catalyst containing platinum can also be effected, as also the reaction of methane and nitrogen oxide to produce hydrogen cyanide at approximately 1000° C..

The rate at which heat is transmitted when operating according to the method of the invention is very large. By way of example a heat transmission of 3×10^7 KCal. per cubic meter of treating space per hour has been obtained in the apparatus illustrated in Figure 13. The solid material in this case was the above mentioned silica sand. The cylindrical sheet in this case had an annular cross section with an internal diameter of 5 centimeters, an external diameter of 6.5 centimeters and a height of 30 centimeters. The mass velocity of sand in this sheet was 10 tons per hour. The temperature of the sand in the fluidized bed in chamber 5 was 750° C. Temperature of sand in the collecting device 6 was 700° C. The residence time of the gaseous fluid within the cylinder which had a capacity of 3 liters was .03 second. In passing through the sheet the temperature of the gaseous fluid was raised from 100° C. to 685° C. in 0.004 second.

I claim as my invention:

1. Process for effecting rapid change in temperature of a gaseous fluid in which the gaseous fluid is contacted with a fluidizable solid by passing the said gaseous fluid transversely through a free falling coherent sheet of fluidizable solid formed by passing the solid from a well fluidized body of the solid through an unrestricted slit-like orifice into a free fall space, said solid having a temperature which varies considerably from that of the said gaseous fluid to be contacted.

2. Process for effecting rapid but intimate contact between a gaseous fluid and a fluidizable solid which comprises forming a well fluidized bed of said solid, flowing said fluidized solid from said bed through a slit-like orifice into a free fall space to thereby create a coherent sheet of the free falling solid and passing the gaseous fluid to be contacted transversely through said sheet.

3. Process according to claim 1 further characterized in that the gaseous fluid consists essentially of hydrocarbons and the temperature of the sheet is sufficiently high that the hydrocarbons are cracked in passing through said sheet.

4. Process according to claim 1 further characterized in that said gaseous fluid consists essentially of at least 2 reactants and that the temperature of the sheet is so chosen that reaction between the reactants takes place during passage of the reactants through said sheet.

5. Process according to claim 1 further characterized

in that said fluidized solid is a powder which is inert chemically and catalytically with respect to the gaseous fluid with which it is contacted.

6. Process according to claim 1 further characterized in that said fluidized solid is at least in part formed of powdered substances which catalyze reactions which take place during passage of gaseous fluid through the sheet.

7. Process according to claim 1 further characterized in that the gaseous fluid contains at least 2 reactants which are allowed to react after being brought to the desired reaction temperature by contact with said sheet.

8. Process according to claim 2 wherein said sheet is in the form of a cylinder and the gaseous fluid to be contacted is introduced within the cylinder.

15. 9. Process according to claim 2 further characterized in that there are two said fluidized beds and two said sheets, one of which is maintained at a high temperature and the other at a low temperature and that the gaseous fluid is passed serially through said sheets thereby providing a very short and substantially square temperature versus time curve.

10. Process according to claim 2 further characterized in that the said slit-like orifice is substantially of plate thickness, is at least 5 millimeters in width, and is positioned above the level of the point of introduction of fluidization gas in said fluidized bed.

11. An apparatus for effecting a rapid change in the temperature of a gaseous fluid which comprises a first upper vessel adapted to maintain a bed of fluidizable solid, gas distributing means in the lower part of said vessel for the introduction of a fluidizing gas to maintain said solid in a well fluidized condition, a slit-like orifice in the lower part of said vessel but above the level of said distributing means, said slit-like orifice being directly above a free fall space surrounded by a wall of a lower chamber below and connected to said first vessel, a second open-topped vessel positioned directly and at some distance below said slit-like orifice, gas distributing means in the lower part of said second vessel for maintaining the contents thereof in a fluidized condition, a third and lower vessel larger and encompassing said second vessel and sealed to said wall of said lower chamber and adapted to catch the overflow of said second vessel, gas distribution means for injecting fluidization gas into the lower part of said third vessel, means for injecting a gaseous fluid into said lower chamber on one side of said slit-like orifice and means for withdrawing contacted gaseous fluid from said lower chamber on the other side of said slit-like orifice.

12. Apparatus according to claim 11 further characterized in that said apparatus is provided with an open-ended shield extending from said first vessel and spaced a short horizontal distance from said orifice said shield being within said lower chamber and extending from said first vessel to a short distance above the top of said second vessel.

13. Apparatus according to claim 12 further characterized in that the apparatus is also provided with a cylindrical baffle open at both ends and positioned below said orifice at a greater horizontal distance from said orifice than the said shield, said baffle extending in height from about the lower end of said shield to a point within and somewhat below the effective top of said second vessel.

14. Process for effecting rapid but intimate contact between a gaseous fluid and a fluidized solid which comprises forming a well fluidized bed of said solid, flowing said fluidized solid from said bed through a slit-like aperture having a minimum confined channel with substantially no constricting hydraulic radius into a free fall space to thereby create a coherent sheet of free falling solid and passing the gaseous fluid to be contacted transversely through said sheet.

15. Process according to claim 14 wherein the coherent sheet is shielded over a substantial part of its

height by a baffle on the side of the sheet through which the contacted gaseous fluid emerges and at a distance from the sheet of about 2 to 10 times the thickness of the sheet.

16. Process for effecting rapid but intimate contact between a gaseous fluid and a fluidized solid which comprises forming a well fluidized bed of said solid, flowing said fluidized solid from said bed through a slit-like orifice into a free fall space at a mass flow rate sufficient to create a coherent sheet of the fluidized free falling solid and passing the gaseous fluid to be contacted transversely through the sheet, said sheet terminating at its lower end in a second fluidized bed of the solid and having its transverse cross-section in the form of a closed figure.

17. Process for effecting rapid but intimate contact between a gaseous fluid and a fluidized solid which comprises forming a well fluidized bed of said solid, flowing said fluidized solid from said bed through a slit-like orifice into a free fall space at a mass flow rate sufficient

10 to create a coherent sheet of the fluidized free falling solid and passing the gaseous fluid to be contacted transversely through the sheet, said sheet extending across the entire section of the confining chamber from wall

5 to wall and terminating at its lower end in a second fluidized bed of solid.
